UNITED STATES PATENT OFFICE.

GEORGE W. MITCHELL, OF LUNENBURG, CANADA.

LIFE-PRESERVER.

SPECIFICATION forming part of Letters Patent No. 741,526, dated October 13, 1903.

Application filed November 18, 1902. Serial No. 131,906. (No model.)

To all whom it may concern:

Be it known that I, GEORGE W. MITCHELL, a citizen of the Dominion of Canada, and a resident of Lunenburg, in the county of Lunenburg, Province of Nova Scotia, Canada, have made a certain new and useful invention in Life-Preservers; and I declare the following to be a full, clear, and exact description of the same, such as will enable others skilled in the art to which it appertains to make and use the invention, reference being had to the accompanying drawings, and to letters of reference marked thereon, which form a part of this specification.

15 The invention relates to life-preserving belts; and it consists in the novel construction and combinations of parts, as hereinafter set forth.

In the accompanying drawings, Figure 1 is 20 a perspective view of the device, and Fig. 2 is a longitudinal section of the two coupled ends of the same on a larger scale.

In the drawings the letter *a* designates the outer rubber or waterproof casing of the belt, 25 which is of tubular character and is provided with a distending-spring *b* and a guard-cord *c*. The ends of the belt are respectively provided with the coöperating parts of a valve-clasp or valvular fastening, said parts consisting of a thimble portion *d* and a tongue portion *e*. The thimble *d*, made of metal or ebonite or other suitable substance, is mainly of cylindrical form, its outer end or mouth *f* being open and its inner end closed, as at *g*, 35 except that the diaphragm is provided with a valve-seat opening *h*. The thimble is seated in one end of the tubular belt, which is wired thereon in a securely waterproof manner, as indicated at *k*. The inner end of the thimble 40 is provided with lugs or connections for securing the ends of the distending-spring *b* and the guard-cord *c*. In the mouth end of the thimble is located the spring-catch *l*, to which is connected the valve *m*, usually of ball form. In the other end of the tubular 45 belt is seated the body *p* of the tongue portion, said body being of cylindrical form and being securely wired in the end of the belt, as indicated. The inner end of this thimble- 50 body is provided with holes, as at *q*, for the at-

tachment of the end of the distending-spring and the end of the guard-cord, which is made slightly shorter than the belt in order to prevent injury to the latter in consequence of excessive strain in use. The tongue-catch *t* 55 is usually of conical form and is provided with a catch shoulder or flanges, which when the tongue is introduced into the mouth of the thimble becomes engaged with the catch end *v* of the spring-catch, and thereby the 60 ends of the belt are securely connected. Usually the conical tongue is provided with a threaded recess designed to engage the threaded neck *w* of the tongue portion. The wall of the mouth portion of the thimble is 65 usually notched at *z* to enable the wearer to more readily press the spring-catch open in disengaging the tongue when it is desired to unfasten the belt.

When not in use, this belt can be contracted in small compass, so as to be easily carried. When it is desired to use the belt, it is extended and the interior spring at once distends it, causing it to become filled with air through the valve-aperture. The belt being 70 then drawn around the body and fastened the engagement of the tongue with the valve-spring clasp causes the valve to be drawn close to its seat and to be held in close engagement therewith by the tension of the belt. In this 75 manner it is designed to prevent the entrance of water or the escape of the air from the belt.

Having described this invention, what I claim, and desire to secure by Letters Patent, is—

1. In a life-preserving belt, the tubular belt, having a distending-spring, the valved diaphragm in one end of said belt, and the two catch members at the ends of the belt, one of which controls the valve of said diaphragm, substantially as specified.

2. In a life-preserving belt, the tubular belt, having a distending-spring, the valved diaphragm in one end of said belt, the spring-catch controlling the valve of said diaphragm, 95 and the tongue at the other end of said belt, and having a catch-shoulder for engagement with said spring-catch, substantially as specified.

3. In a life-preserving belt, the tubular 100

belt, having a distending-spring and guard-cord, the diaphragm in one end of said belt, and having a valve-seat, the spring-catch carrying a ball-valve for said seat, and the 5 tongue at the other end of said belt, and having a catch-shoulder for engagement with said spring-catch, substantially as specified.

In testimony whereof I affix my signature in presence of two witnesses.

GEORGE W. MITCHELL.
